UNITED STATES PATENT OFFICE.

HENRY GRUSONG, OF CRESSON, PENNSYLVANIA.

WHEEL-MOUNT.

1,093,264.

Specification of Letters Patent. Patented Apr. 14, 1914.

Application filed September 17, 1913. Serial No. 790,266.

To all whom it may concern:

Be it known that I, HENRY GRUSONG, a citizen of the United States, residing at Cresson, in the county of Cambria and State 5 of Pennsylvania, have invented certain new and useful Improvements in Wheel-Mounts, of which the following is a specification, reference being had to the accompanying drawings.

10 This invention comprehends certain new and useful improvements in trolley poles and heads and has for its primary object to provide a trolley pole and head which will be of such construction and operation 15 as to allow the trolley wheel mounted in the head to turn to various positions without leaving the trolley wire.

Another object is to provide a device of this character in which the portion of the 20 trolley pole upon which the head is mounted will be free to rotate limited distances in opposite directions while the head is mounted upon said portion of the trolley pole in such manner that said head may be free to 25 turn as far as necessary in either direction when the car is turning the corner or rounding a curve, without danger of the wheel leaving the trolley wire, as sometimes happens in the ordinary construction.

30 A further object is to generally improve and simplify the construction and operation of devices of this character and increase the efficiency of the same.

With the above and other objects in view, 35 my invention consists in certain novel constructions, combinations, and arrangements of parts to be hereinafter more fully described, claimed, and illustrated in the accompanying drawings, in which,

40 Figure 1 is a longitudinal sectional view through the complete device; Fig. 2 is an elevational view of the same; Fig. 3 is a detail cross sectional view on the line 3—3 of Fig. 1, looking in the direction indicated

45 by the arrow; Fig. 4 is a top plan view of the device; Fig. 5 is a detail cross sectional view on the line 5—5 of Fig. 1, with the current conducting wire removed; and Fig. 6 is a detail elevational view of the trolley 50 head removed, said view showing the rear or inner face of the same.

Referring more specifically to the drawings in which similar reference characters 55 designate corresponding parts throughout the several views, 1 designates the main portion of the trolley pole, upon the end of

which is mounted a stationary sleeve 2 through which is rotatably mounted the portion 3 of the trolley pole extending parallel with the main portion of the trolley pole and forming a continuation of the same. The rotatable portion of the trolley pole has its opposite ends extended through the sleeve 2 and has a collar 4 mounted on its lower extended end with the radially directed stop ears 5 mounted thereon at substantially diametrically opposite points and adapted for engagement at times with the main portion 1 of the trolley pole to limit rotation of the rotatable portion 3 of said trolley pole. A bearing block 6 is mounted upon the upper extended end of the rotatable portion 3 of the trolley pole and has the socket 7 formed therein and extending inwardly from one face 8 thereof to receive the bearing sleeve 9 projecting laterally from the corresponding flat face 10 of the trolley head 11. A bearing member 12 extends longitudinally through the center of the socket 7 and bearing and sleeve and has 80 one end mounted in the end wall of the socket while its opposite end extends through the face 10 of the trolley head 11 and has a nut or other suitable means 13 secured thereon, the first mentioned end of the bearing member having the head 14 formed thereon, which head is preferably countersunk in the outer face of the bearing block 6.

The trolley head 11 is suitably forked, as shown at 15, and has a shaft 16 mounted in 90 its forked portion with a trolley wheel 17 loosely mounted thereon.

It will be understood that the conducting wire 18 may be connected with the stationary sleeve 2, as shown at 20, or in any other 95 suitable manner, and secured to the main portion 1 of the trolley pole, as shown at 21. It will also be understood that the sleeve 2 is suitably insulated from the main portion of the trolley pole.

100 From the foregoing, it will be clearly apparent that I have constructed and connected the trolley pole and head in such manner that the upper or extended portion of the trolley pole may turn as far as necessary in a plane at right angles to the plane in which the extended portion of the trolley pole turns, when the car is rounding a curve or turning a corner, without danger of the trolley wheel 17 leaving the trolley wire, 110 as sometimes happens in the ordinary construction.

While I have shown the preferred embodiment of my invention, it will be understood that minor changes in the details of construction and arrangements of parts may be made within the scope of the appended claim without departing from the spirit of my invention or sacrificing any of the advantages of the same.

What I claim is:—

- 10 A device of the class described comprising a trolley pole including a stationary portion and a rotatable portion positioned parallel to the stationary portion and beyond the free end of the same, a bearing collar mounted on the stationary portion, said rotatable portion being rotatably mounted in the bearing
- 15

collar, a bearing block carried by one end of the rotatable portion, a trolley head mounted upon the bearing block and adapted for rotation in a plane at right angles to the plane in which the rotatable portion of the trolley pole is adapted to rotate, a trolley wheel mounted in said head, and means mounted upon the opposite end of the rotatable portion of the trolley pole for limiting movement of the same in either direction.

In testimony whereof I hereunto affix my signature in the presence of two witnesses.

HENRY GRUSONG.
